US0D1060681S

(12) **United States Design Patent** (10) Patent No.: **US D1,060,681 S**
(45) Date of Patent: ** Feb. 4, 2025

(54) **DEFIBRILLATOR**

(71) Applicant: **CELLAED LIFE SAVER PTY LTD**,
Elanora Heights (AU)

(72) Inventors: **Marco Heusdens**, Taipei (TW);
Vincent Chen, Taipei (TW); **Berling Tang**, Taipei (TW)

(73) Assignee: **Cellaed Life Saver PTY LTD**, Elanora Heights (AU)

(**) Term: **15 Years**

(21) Appl. No.: **29/845,616**

(22) Filed: **Jul. 8, 2022**

Related U.S. Application Data

(63) Continuation of application No. 29/772,109, filed on Feb. 26, 2021, now Pat. No. Des. 959,668.

(30) **Foreign Application Priority Data**

Aug. 31, 2020 (AU) 202014731

(57) **CLAIM**

The ornamental design for a defibrillator as shown and described.

DESCRIPTION

FIG. 1 is a top perspective view of the defibrillator showing the new design;

FIG. 2 is a bottom perspective view thereof;

FIG. 3 is a top view thereof;

FIG. 4 is a bottom view thereof;

FIG. 5 is a front view thereof;

FIG. 6 is a back view thereof;

FIG. 7 is a left view thereof; and,

FIG. 8 is a right view thereof.

The broken lines illustrate portions of the defibrillator that

form no part of the claimed design.

1 Claim, 6 Drawing Sheets
